UNITED STATES PATENT OFFICE.

HERBERT S. MILLS, OF OAK PARK, ILLINOIS.

VENDING-MACHINE.

1,038,178.

Specification of Letters Patent. Patented Sept. 10, 1912.

Application filed December 23, 1911. Serial No. 667,539.

To all whom it may concern:

Be it known that I, HERBERT S. MILLS, a citizen of the United States, residing at Oak Park, in the county of Cook and State of Illinois, have invented a new and useful Improvement in Vending-Machines, of which the following is a specification.

This invention relates to an improvement in the class of coin-controlled machines for vending measured quantities of merchandise sold in bulk and stored for the supply in a receptacle surmounting the case of the machine to be fed by gravity to the delivery mechanism.

The present machine has been devised more especially for the automatic vending of salted peanuts, though it is also useful for the vending of other nuts and articles in bulk.

In the accompanying drawings, Figure 1 shows the machine by a view in side elevation; Fig. 2 is a broken view of the same in front elevation; Fig. 3 is a section on the irregular line 3, Fig. 1; Fig. 4 is a section 25 on the line 4, Fig. 3, but showing a portion of the top of the casing to which a brush is secured; Fig. 5 is a broken section on line 5, Fig. 4; Fig. 6 is a section on line 6, Fig. 2; Fig. 7 is a section on line 7, Fig. 3, and 30 Fig. 8 is a section on line 8, Fig. 3.

The casing 9, shown of rectangular shape, with rubber-tipped feet 10 at the corners of its base 11, has an opening 12 in its top 13 which is covered by the mouth of a glass 35 jar or receptacle 14 for salted peanuts, or the like, provided with a lock-equipped hinged cover 15. Adjacent to the receptacle is mounted in an opening through the top a metal head 16 having a coin-insertion 40 slot 17, at the ends of which project toward each other, into the coin-path, spring-pressed hard-metal blocks 18 (Fig. 8 provided with sharp opposing ends 19. A proper coin (as a penny) used for operating 45 the machine will force these blocks apart by inserting it through the slot, but they will, under the force of the springs, indent or cut into a lead, paper or other disk of soft material attempted to be used for the operation and arrest the passage between them, thus frustrating such attempt at fraudulent 50 operation.

A box-like body 20, which may be of wood, is fastened to bear at its upper side 55 flatwise against the under face of the top 13 and contains in that side an opening 21,

shown of crescent shape, to register with the opening 12, in which latter depends rigidly a brush-device 22 for the purpose hereinafter explained. In the bottom of the box 20 is provided, to one side of its center, a discharge-opening 23 registering with the inner end of a delivery-spout 24 projecting through the front wall of the casing and having a finger-equipped hinged lid 25 covering its outer discharge end and held yieldingly closed by a spring 26 (Fig. 6). A cup 27, to receive the discharge from the spout, is pivotally supported between arms 28 extending from the front edge of the base 11. In the box 20 is centrally journaled, to be rotated therein horizontally, a wheel 29 containing four similar pockets 30 equidistant apart about its center, to register with the opening 12, for filling the pockets by gravity from the receptacle 14, and to register in succession with the opening 23 for discharging the contents of one pocket into the spout 24 by each operation of the machine. It is to be noted that the crescent shaped opening 21 is cut eccentrically of the center of rotation of the pocket-equipped wheel 29, so that as the wheel is rotated with its upper surface in contact with the under surface of the box-top 20 the edges of the crescent shaped opening will produce a shear across the surface of the wheel and assist the brush in keeping the top of the wheel clear of salt and crumbs of the nuts and prevent the same working into the operating mechanism.

A metal plate 31 is fastened to one end of the box 20 for supporting a coin-chute 32 to register at its receiving-end with the slot 17 and at its opposite end with the coin-operated mechanism. This mechanism comprises a horizontal shaft 33 journaled near its outer end in the plate and at its inner end in an angular bearing 34 depending from the bottom of the box 20, where the shaft carries a beveled gear 35 meshing with a similar gear 36 on a vertical shaft 37 journaled in that bearing and extending centrally through the box 20 to carry it. On the outer end of the shaft 33 is secured a ratchet-wheel 38, held against reverse turning by a spring-pressed detent 39, and provided centrally on its inner face with a star-wheel 40 presenting shallow V-shaped edge-depressions between its four points, and about its outer face, near the periphery, with four studs 41 equidistant apart. A

lever 42, fulcrumed at one end to the plate and held at its opposite end by a spring 43, crosses the star-wheel and is formed between its ends with a V-shaped section to engage 5 successively with the depressions in the star-wheel and brake the ratchet-wheel against excessive turning when operated as herein-after described. The plate also carries an ordinary Veeder counter 44 having a crank 10 45 (Fig. 8) on its shaft connected with a finger 46 projecting from the lever 42, whereby each operation of the machine, in turning the star-wheel through a quarter-revolution, moves the lever to actuate the 15 counter to register the operation thereon. The shaft 33 carries loosely on its outer end, which is pointed as shown, a disk 47 having on its outer face a central boss 48 containing a diametrical slot 49 and with which is connected at a stud 50 a retracting spring 51. A finger 52 projects from the periphery of the disk to engage a stop 53 in its path on the plate for preventing undue turning of the disk by the force of its retracting spring; 20 and an arc-shaped flange 54 is provided on the inner face of the disk to be concentric and coöperate with the studs 41 in succession.

The side of the casing which covers the 30 plate 31 is key-locked and removable, and has journaled in it a shaft 55 carrying on the inner end a head 56 provided on its face with a diametrical key-portion or projection to register with and enter the slot 49 35 for engaging the shaft 55 with the shaft 33. The pointed end of the shaft 33 passes through a central opening in the said projection to enter a socket 57 in the head 56 for centering the shaft 55, which carries on 40 its outer end an operating crank-handle working, to limit its throw, between stops 58 on the outer face of the removable casing-side (Fig. 1).

To operate the machine with the receptacle supplied, say, with salted peanuts filling the cups 30 in registry with the opening 21, the procedure is as follows: A coin 59 (Fig. 7) pressed through the slot 17 past the blocks 18, drops through the chute 50 against the shaft 33 and between a stud 41 and the adjacent end of the flange 54. Thereupon turning the crank turns the disk 47 to bear the end of the flange 54 against the coin in its path, and presses the coin 55 against the opposing stud 41 to turn the ratchet until the coin drops from its position of lodgment. Thus turning the ratchet turns the shaft 33 against the resistance of

the brake-lever upon the star-wheel, and the shaft 37 to turn the wheel 20 through a 60 quarter revolution, thereby bringing a pocket into registration with the opening 23 to discharge its contents into the spout. Further turning of the wheel by a single operation of the machine is prevented by the coin-dropping its connection-forming position between the flange 54 and a stud 41 when the wheel has made a quarter-turn, as required to produce the aforesaid registration. Upon releasing the handle it is retracted by 70 the spring to the initial position against the upper stop 58, ready for a repetition of the operation upon inserting another coin to bring the next-succeeding pocket into position to discharge. 75

The brush 22 is an important feature of the device in serving to keep the upper surface of the wheel free from salt and other matter accumulating upon it from the nuts. Without the brush to prevent such accumulation it would clog and disorganize the machine. The hinged spout-lid 25 is another important feature rendering the machine sanitary, since it prevents the operator from placing his hand under the discharge-end of the spout and requires him to manipulate the cover to open the spout for producing the discharge therefrom into the cup 27, which adds to the sanitary property of the machine by being adapted to be tilted to 90 empty it of its contents rather than scooping them out by hand. 85

What I claim as new and desire to secure by Letters Patent is—

In a vending machine of the character described, the combination of a casing having a top-opening, a box in the casing having a top receiving-opening located beneath the opening in the casing and a bottom discharge-opening, a pocket-containing receiving and delivery wheel centrally journaled in the box, with its upper surface moving in contact with the box-top, the top receiving-opening being substantially crescent shaped and cut eccentrically of the journal of the 105 wheel, a brush mounted in said crescent shaped opening adjacent its central portion and extending across the greater portion thereof, said brush depending through said opening into contact with the upper surface 110 of said delivery wheel, and means for rotating said wheel. 100

HERBERT S. MILLS.
